UNITED STATES PATENT OFFICE.

ALBERT L. SAWYER, OF OLD TOWN, MAINE.

CURRENT TAKE-OFF CLAMP.

Application filed September 18, 1926. Serial No. 136,273.

This invention relates to electrical connecting devices, particularly to the general class of line tappers, and has for its object the provision of a novel clamping device adapted to be engaged upon a high tension conductor for taking off current for any purpose whatsoever, as for instance to drive a motor, operate a transformer or perform any other similar function.

10 An important object of the invention is to provide a device of this character so constructed and arranged that it may be manipulated from the ground, the operating means being detachable after the clamp is in

15 place on a conductor.

A more specific object is to provide a clamping device of this character having a spring means for normally holding it in clamping engagement upon a conductor and 20 having screw operated cam means for effecting release or disengagement from the conductor.

Still another object is to provide a device of this character in which the parts are so 25 arranged as to avoid any appreciable heating effects on the spring, thereby eliminating any deteriorating results which might occur.

An additional object is the provision of a clamp of this character which will be simple 30 and inexpensive to manufacture, easy to apply or remove, positive in action, efficient and durable in service, and a general improvement in the art.

With the above and other objects and advantages in view, the invention preferably 35 consists in the arrangement and combination of parts and detailed structural features to be hereinafter more fully described and claimed, and illustrated in the accompanying 40 drawing in which:

Figure 1 is a perspective view showing the device in actual use and illustrating the act of engaging it upon or releasing it from a conductor.

45 Figure 2 is a side elevation of the clamp on a much larger scale showing it in released position.

Figure 3 is a longitudinal section through the clamp showing the operating means removed and the parts in operative or clamping relation, and

50 Figure 4 is a cross sectional view taken on the line 4-4 of Figure 2 to show the shape of the cam member.

55 Referring more particularly to the drawings, I have shown the device as comprising

a body member 10 of suitable size and shape as well as material, though the body must necessarily be of metal so as to be a conductor of electricity. Obviously, this member may conveniently be formed as a casting and it is here represented as provided at one side with ears 11 between which is pivoted, at 12, a clamping plate 13 normally urged toward the body 10 as by means of a coil 60 spring 14 surrounding a bolt or pin 15 which extends through an opening 16 in the plate 13 and which is suitably anchored to the body. This pin or bolt has a head 17 constituting an abutment for one end of the 65 spring, the other end of which engages against the outer face or surface of the clamping plate 13. While it is conceivable that any suitable anchoring means may be provided for holding the pin or bolt with 70 respect to the body, the body is here shown as having a hole 18 through which the pin or bolt extends, a cotter or other transverse element 19 passing through the pin or bolt as clearly indicated in Figure 3 for holding 75 the parts against accidental separation. The device is intended to be clampingly engaged upon a conductor A and it is preferable that the body or clamping plate 13, or both, be provided with a groove or notch 20 within 80 which the conductor may be engaged.

The device is intended for use upon high tension conductors which, as illustrated in Figure 1, are generally suspended some distance above the ground, and for this reason 85 I make use of a pole 21 of suitable length carrying a head 22 from which projects a stem 23 terminating in a reduced threaded extension 24. At the base of the stem is provided an enlargement 25 which defines a 90 shoulder 26, and the extension 24 is preferably provided with a guide tip 27. The body 10 is provided with laterally extending 95 vertically spaced arms 28 and 29, the former of which is provided with a smooth hole 30 of a size to receive the stem 23, and the latter of which is formed with a threaded hole 31 to receive the threaded extension 24, the tip 27 serving as a guide to facilitate connection of 100 the head on the pole with the clamping 105 device.

The body has connected therewith a conductor 32 which may be held in any desired manner as for instance by being engaged within a socket 33 in the body and clamped 110 by set screws 34 or the like. This conductor 32 is of course intended to be connected with

whatever electrical apparatus is to be fed with current.

As stated above, the spring 14 operates to hold the device in clamping relation upon the conductor A. In order that the device may be released, I provide a cam member 35 pivoted at 36 within an opening 37 in the body 10 and having a curved surface 38 adapted to be brought into engagement with the inner face of the clamping plate 13. The other end of the cam is formed with a fork 39 which receives the reduced extension 24 and which is adapted to be engaged by the shoulder 40 at the juncture of the stem 23 with the extension 24 so that when the pole is rotated in a clockwise direction the cam will be rocked upon its pivot 36 and will swing the clamping plate 13 outwardly or away from the body 10 to disengage the conductor A.

It is of course clear that the device may be used in connection with any overhead conductors whether the current carried thereby have a low or high tension and in Figure 1 I have clearly illustrated the manner in which the device is employed. Naturally there are no restrictions as to the type of mechanism or apparatus to be operated, that disclosed at B in Figure 1 being simply for purposes of illustration.

Assuming that it is intended to engage the device upon a conductor, it is mounted upon the pole by engaging the stem 23 and reduced extension 24 within the holes in the arms 28 and 29, the threaded extension 24 being screwed into the hole 31 only partly so that the cam 35 will be in its normal or idle position as shown in Figure 3. The operator then manipulates the pole to bring the device over the conductor A and then pulls downwardly upon it so that the conductor will be forced to enter between the body 10 and the clamping plate 13. It will be noted that the lower or free end of the plate 13 is curved away from the body to define a flaring entrance opening 41 to the space between the clamping plate and the body. When the device is pulled down onto the conductor, the spring 14 is compressed and the conductor is moved along until it snaps into the groove or notch 20. The operator then rotates the pole to unscrew the threaded extension 24 from within the hole 31 and the pole, with the head thereon, is then detached from the clamping device by the simple method of pulling it away. The spring 14 provides the necessary tension means for holding the conductor A firmly clamped.

When it is desired to disengage the device from the conductor the operator manipulates the pole properly so that the head thereon may be connected with the clamping device, the extension 24 being passed through the hole 30 and screwed into the

hole 31, and the stem 23 entering the hole 30. The operator turns the pole in a clockwise direction to bring the shoulder 40 into engagement with the fork 39 so that the cam 35 will be rocked to bring the face 38 thereof against the clamping plate 13 to move the latter away from the conductor. The operator then lifts the device off from the conductor.

From the foregoing description and a study of the drawing it will be apparent that I have thus provided a simply constructed, inexpensive and yet very efficient device for the purpose specified and one which will be a great time and labor saver whenever it is desired to tap a line wire for taking off current. It is believed that the construction, operation and advantages will be readily apparent to one skilled in the art without further explanation.

While I have shown and described a preferred embodiment of the invention, it should be understood that I reserve the right to make such changes in the form, construction and arrangement of parts as will not depart from the spirit of the invention or the scope of the subjoined claims.

Having thus described the invention, I claim:

1. In a device of the character described, a body member, a spring pressed clamping plate cooperating therewith, means mounted on the body member normally out of engagement with the clamping member and movable to release the latter, and means connectible with the body member for handling the same and controlling said releasing means from a remote point.

2. The combination of a clamping device comprising a body member and a spring pressed member movably connected therewith, a cam carried by the body member and movable to engage said movable member for moving it away from the body member, a handle device adapted to be engaged with the body and to be disengaged therefrom, and means on the handle device for moving said cam.

3. A clamping device of the character described comprising a body member, a clamping plate pivoted thereon, spring means urging said clamping plate toward the body into clamping relation thereto, in combination with a handle member carrying a head, said head being detachably connectible with the body, and means operable by movement of said head to swing said clamping member away from the body.

4. A clamping device of the character described comprising a body member, a clamping plate pivoted thereon, spring means urging said clamping plate toward the body into clamping relation thereto, in combination with a handle member carrying a head, said head being detachably connectible with the body.

ible with the body, and means operable by movement of said head to swing said clamping member away from the body, said means comprising a cam pivoted on the body and movable into engagement with the clamping member, said cam having a portion engageable by said head to be moved thereby.

5. In combination, a clamping device comprising a body formed with spaced arms, one arm having a threaded opening therein and the other having a smooth opening, a spring pressed plate member pivoted on the body and cooperating therewith to define a clamp, a cam pivoted on the body and adapted to engage the plate for moving the same out of clamping relation to the body, a pole carrying a head including portions engageable through said opening, and means on said head engageable with said cam for 20 moving the same into releasing position.

6. In a device of the character described, a body having spaced arms thereon, one having a smooth opening and the other a threaded hole, a plate member pivoted on the body, spring means urging said plate member into clamping relation to the body, said body having an opening therein, a cam pivoted within the opening and normally 25 out of engagement with said pivoted plate member, in combination with a handle carrying a head having a stem portion slidably engageable through said smooth hole and having a reduced threaded extension adapted to be screwed into said threaded hole, and a shoulder engageable with the cam for swinging the same to release the clamping member, the cam having a fork 30 accommodating said reduced extension and disposed in the path of movement of said shoulder.

carrying a head having a stem portion slidably engageable through said smooth hole and having a reduced threaded extension adapted to be screwed into said threaded hole, and a shoulder engageable with the cam for swinging the same to release the clamping member.

7. In a device of the character described, a body having spaced arms thereon, one having a smooth opening and the other a threaded hole, a plate member pivoted on the body, spring means urging said plate member into clamping relation to the body, said body having an opening therein, a cam pivoted within the opening and normally 40 out of engagement with said pivoted plate member, in combination with a handle carrying a head having a stem portion slidably engageable through said smooth hole and having a reduced threaded extension 45 adapted to be screwed into said threaded hole, and a shoulder engageable with the cam for swinging the same to release the clamping member, the cam having a fork 50 accommodating said reduced extension and disposed in the path of movement of said shoulder.

In testimony whereof I affix my signature.

ALBERT L. SAWYER.
